UNITED STATES PATENT OFFICE.

ELEAZAR PARMLY, JR., OF CHICAGO, ILLINOIS.

DESIGN FOR A PHONOGRAPH CABINET OR SIMILAR ARTICLE.

Application filed June 14, 1928. Serial No. 27,132. Term of patent 14 years.

To all whom it may concern:

Be it known that I, ELEAZAR PARMLY, Jr., a citizen of the United States, residing at Chicago, in the county of Cook and State of Illinois, have invented a new, original, and ornamental Design for Phonograph Cabinet or Similar Article, of which the following is a specification, reference being had to the accompanying drawing, forming part thereof.

cabinet, and said cabinet is provided with straight grain borders and burled panels.

Figure 2 is an end view of this cabinet.

I claim:

The ornamental design for a phonograph cabinet or similar article as shown.

In witness whereof, I hereunto subscribe my name this 7th day of June, 1928.

ELEAZAR PARMLY, JR.
